G. W. HOWES

STOVE

Filed Oct. 16, 1925

UNITED STATES PATENT OFFICE.

GEORGE W. HOWES, OF DOWAGIAC, MICHIGAN, ASSIGNOR TO THE BECKWITH COMPANY, OF DOWAGIAC, MICHIGAN.

STOVE.

Application filed October 16, 1925. Serial No. 62,796.

To all whom it may concern:

Be it known that I, GEORGE W. HOWES, a citizen of the United States, residing at Dowagiac, county of Cass, State of Michigan, have invented certain new and useful Improvements in Stoves, of which the following is a specification.

This invention relates to improvements in stoves.

10 The main objects of this invention are to provide an improved door construction for ovens and the like having a concealed hinge which is simple and economical in structure, attractive in appearance, and one in which 15 the enamel or finish of the door is effectively protected.

Objects relating to details and economies of construction and operation of my invention will definitely appear from the detailed 20 description to follow.

I accomplish the objects of my invention by the devices and means described in the following specification. The invention is clearly defined and pointed out in the 25 claims.

A structure which is a preferred embodiment of my invention is clearly illustrated in the accompanying drawing, forming a part of this application, in which:

30 Fig. 1 is a fragmentary perspective view of a stove embodying the features of my invention.

Fig. 2 is a fragmentary section on a line corresponding to line 2—2 of Fig. 1.

35 Fig. 3 is a detail horizontal section on a line corresponding to line 3—3 of Fig. 1.

Fig. 4 is a perspective view in the flat of the combined bearing and buffer member constituting an element of this invention.

40 In the drawing similar reference characters refer to similar parts throughout the several views, and the sectional views are taken looking in the direction of the little arrows at the ends of the section lines.

45 Referring to the drawing, I have shown only such parts of a stove door casing and door as are deemed necessary to disclose my invention. I have shown only one of the hinge units but it will be understood that these are duplicated.

50 My improved door casing, designated generally by the numeral 1, is provided with an inset door jamb 2 for the door 3. The door casing comprises a downwardly curved bottom member 4 and inwardly facing

channeled upright members 5. These upright members have recesses 6 at their lower ends adapted to receive the laterally projecting portions 7 of the door 3. These recesses have slots 8 therein through which 60 the hinge arms 9 are disposed, these arms projecting inwardly and downwardly from the door.

I provide combined bearing and buffer members or clips 10 which are arranged 65 through the slots 8 and curved to provide bearings for the coacting bearing recesses 11 in the edges of the hinge member 9. These bearing members are secured with their outer ends 12 projecting downwardly 70 and conformed to the curved portion 13 of the bottom member 4 of the door casing which extends below the slots 8, the front ends constituting buffers and wear members protecting the finish of the casing so 75 that the enamel or other finish is not broken or chipped by the swinging of the door.

In the embodiment illustrated, the bearing member is provided with a tongue 15 arranged through slots 16 in the casing and 80 through slots 17 in the inner ends of the bearing members, the tongues being bent down to secure these clips or bearing members in place. The outer edges 14 of the hinge members 9 are curved and the curved 85 portions terminate in stop shoulders 18 with which the stops 19 mounted on the inner side of the door casing coact, these stops 19 projecting downwardly into engagement with the curved surfaces 14 serving as retaining 90 means for the hinge arms and also, as stated, as stops. The counterbalancing springs 20 are secured at 21 below the door and have loops 22 engaging the hooks 23 on the inner ends of the arms. The counterbalancing 95 springs are not of sufficient strength to lift the door when it is in its open horizontal position but do serve to retain the same in closed position and lessen the closing effort.

With the parts thus arranged, I provide a structure which is simple and economical to produce and at the same time is very attractive in appearance and, as stated, the finish of the door casing is effectively 105 protected.

Having thus described my invention, what I claim as new and desire to secure by Letters Patent, is:

1. In a stove, the combination of a casing 110

having an inset door jamb and comprising a downwardly curved bottom member and inwardly facing channeled upright members having recesses at their lower ends, the recesses having slots therein, the curved portion of the bottom member extending below said slots, bearing members disposed through said slots with their outer ends conformed to the face of the bottom member, their inner ends having slots therein, said bearing members having tongues on their outer ends disposed through said casing bottom member and engaged in said slots in their inner ends whereby said bearing members are retained in position, a door having laterally projecting portions at its lower edge adapted to close into said recesses and provided with inwardly projecting hinge arms disposed through said slots having curved bearings in their lower edges coacting with said bearing members, the inner edges of said hinge arms being curved and having stops at the rear end thereof, and stop members mounted on said casing to coact with said stops on said arm and constituting retaining members coacting with said curved surfaces of said arms.

2. In a stove, the combination of a casing having an inset door jamb and comprising a downwardly curved bottom member and inwardly facing channeled upright members having recesses at their lower ends, the recesses having slots therein, the curved portion of the bottom member extending below said slots, bearing members disposed through said slots with their outer ends conformed to the face of the bottom member, a door having laterally projecting portions at its lower edge adapted to close into said recesses and provided with inwardly projecting hinge arms disposed through said slots having curved bearings in their lower edges coacting with said bearing members, the inner edges of said hinge arms being curved and having stops at the rear end thereof, and stop members mounted on said casing to coact with said stops on said arm and constituting retaining members coacting with said curved surfaces of said arms.

3. In a stove, the combination of a casing having an inset door jamb and comprising upright members having recesses at their lower ends, the recesses having slots therein, bearing members disposed through said slots

with their outer ends projecting below the same and having tongues disposed through said casing, their inner ends being slotted to receive said tongues whereby said bearing members are retained in position, and a door having laterally projecting portions at its lower edge adapted to close into said recesses and provided with inwardly projecting hinge arms having bearings in their lower edges coacting with said bearing members.

4. In a stove, the combination of a casing having an inset door jamb and comprising upright members having recesses at their lower ends, the recesses having slots therein, bearing members disposed through said slots with their outer ends projecting below the same, and a door having laterally projecting portions at its lower edge adapted to close into said recesses and provided with inwardly projecting hinge arms having bearings in their lower edges coacting with said bearing members.

5. In a stove, the combination of a casing having slots therein, bearing members disposed through said slots with their outer ends projecting below the same and having tongues disposed through said casing, their inner ends being slotted to receive said tongues whereby said bearing members are retained in position, and a door provided with inwardly projecting hinge arms having bearings in their lower edges coacting with said bearing members.

6. In a stove, the combination of a casing having slots therein, bearing members disposed through said slots with their outer ends projecting below the same, and a door provided with inwardly projecting hinge arms having bearings in their lower edges coacting with said bearing members.

7. In a door, the combination of a casing having an inset door jamb and comprising a downwardly curved bottom member and inwardly facing channeled upright members having recesses at their lower ends, the recesses having slots therein, and a door having laterally projecting portions at its lower edge adapted to close into said recesses and provided with inwardly projecting hinge arms disposed through said slots.

In witness whereof I have hereunto set my hand.

GEORGE W. HOWES.
